US00D436375S

(12) **United States Design Patent** (10) Patent No.: **US D436,375 S**
Rosenbaum (45) Date of Patent: ** Jan. 16, 2001

(54) **WRITING INSTRUMENT WITH BULBOUS GRIP**

(75) Inventor: **Barry Rosenbaum**, West Bloomfield, MI (US)

(73) Assignee: **Advance Watch Company, Ltd.**, Warren, MI (US)

(**) Term: **14 Years**

(21) Appl. No.: **29/109,871**

(22) Filed: **Aug. 24, 1999**

(51) LOC (7) Cl. **19-06**

(52) U.S. Cl. **D19/51; D19/55; D19/57**

(58) Field of Search D19/35, 36, 41-51, D19/53-58, 81-85; 401/6, 7, 88, 99, 100, 110-116, 209, 243-247, 202, 262
